Letters Patent No. 71,702, dated December 3, 1867.

IMPROVED LINE-HOLDER.

The Schedule referred to in these Letters Patent and making part of the same.

TO ALL WHOM IT MAY CONCERN:

Be it known that I, SAMUEL J. CLARK, of the city of Detroit, in the county of Wayne, in the State Michigan, have invented a new and improved Line-Holder; and I do declare that the following is a full and accurate description of the same, reference being had to the accompanying drawings, and to the letters of reference marked thereon, being made a part of this specification.

The nature of my invention consists in using the reversible wheel A, with the cap C, upon the plate D, to stop or hold a cord, rope, or strap E, against the stop B, as in Figures 1 and 2, for holding clothes-lines, or other cords or straps, and in Figure 5 for holding a curtain-cord or strap, or in Figure 4 as a window-stop. Figure 3 represents a cable-stop with lever G to fit into socket F, for the purpose designed.

What I claim as my invention, and desire to secure by Letters Patent, is—

The eccentric wheel A, stop B, plate D, and the cap C, or substantially the same, for the purpose designed.
